CLAIM

The ornamental design for a vane module for a wind turbine, as shown and described.

DESCRIPTION

FIG. 1 is a front elevation view of a vane module for a wind turbine showing our new design;

FIG. 2 is a right side elevation view thereof, the left side being a mirror image;

FIG. 3 is a top plan view thereof;

FIG. 4 is a bottom plan view thereof;

FIG. 5 is a bottom perspective view thereof; and,

FIG. 6 is a top perspective view thereof.

1 Claim, 5 Drawing Sheets
